UNITED STATES PATENT OFFICE.

HARRY A. CUMFER, OF CHICAGO, ILLINOIS, ASSIGNOR OF ONE-HALF TO THE FLINT-KOTE COMPANY, OF BOSTON, MASSACHUSETTS, A CORPORATION OF MASSACHUSETTS.

ROOFING ELEMENT.

Application filed October 2, 1924. Serial No. 741,117.

This invention relates to improvements in method of producing roofing strips and product thereof, and specifically contemplates cutting from a sheet of roofing material individual roofing strips without any waste of material, which, when laid on a roof, are self-spacing relative each other to present an attractive appearance and contrasting fields of light, dark and shaded intermediate areas.

Briefly, a continuous sheet of previously waterproofed felt having a granular surfacing on one or both sides is fed to a roofing machine, severed transversely entirely across its width and simultaneously or subsequently having a plurality of sets of short opposed right angular incisions produced adjacent and relative to the severed edge. The spaces between these incisions are then folded over the body of the strip, preferably upon the exposed granular face thereof.

From the standpoint of economy of production, ease and certainty of accurate spacing on the roof, attractiveness of design and speed with which the shingles can be laid on a roof, the product of this invention possesses many advantages.

In the drawings:

Fig. 1 is a plan view of an individual shingle strip severed from a sheet of roofing material, illustrating the manner of making the incisions.

Fig. 2 is a plan view of the strip, with the tab portions formed by the incisions folded back upon the face of the strip.

Fig. 3 is an edge view of the construction shown in Fig. 2.

Fig. 4 is a view similar to Fig. 3, of a slightly modified form of construction.

Fig. 5 is a plan view of a plurality of strips assembled on a roof.

Referring in details to the drawings, 1 designates an individual shingle strip of rectangular shape cut from a continuous sheet of previously prepared roofing material, consisting of a felt base saturated with a waterproofing compound and having imposed on one or both surfaces a granular surface of any predetermined or contrasting colors, red, green, brown, etc. In the preferred form of construction, the exposed surface only has granular material imbedded therein, the

lower surface presenting the color of the waterproofing material.

Adjacent the line of transverse severance 2, as the continuously advancing sheet is fed forward to be transversely severed entirely across the width, are either simultaneously or subsequently produced a plurality of sets of opposed perpendicular incisions 3 terminating preferably short of the central transverse cross section of the sheet to produce the tabs 4. Preferably as part of the same operation, these tabs 4 are folded back upon the exposed surface of the strip (Fig. 2), the upper edge 5 terminating about midway transversely of the strip. The granular material is designated as 6 and may be green, gray, red, brown, slate or other desired color, while the exposed portion 7 of the folded tab is preferably devoid of any granular surfacing and presents a darker color, for instance, black, where asphalt is used as the waterproofing medium.

The shingles when laid on a roof (see Fig. 5) present a roof having contrasting light, dark and shaded areas. The lower edges 2 of successive overlying shingles may about directly upon the butt edge 5, thus self-spacing individual shingles relative to each other. In the embodiment of my invention explained above, the entire area of the tab 4 may be attached to the body portion of the strip (Fig. 3).

However, as shown in Fig. 4, the upper portion 8 of the tab may be left unattached, thus producing pockets 9 for the edges of overlying shingles. It will be seen that there will be no waste in cutting shingle strips in accordance with this invention, from a continuous sheet of roofing material, while at the same time producing a self-spacing shingle strip.

I claim as my invention:

1. As a new article of manufacture, a strip of roofing material substantially rectangular in shape, provided with spaced rectangular notches extending inwardly from the lower edge and integrally connected overlying portions folded upon and attached to the upper surface of the strip, said integrally connected portions comprising the material severed between individual sets of notches, a portion of the outer end of each overlying folded portion forming a shoulder

with which the lower edge of an overlying strip is adapted to align and abut.

2. A new article of manufacture comprising a strip of flexible roofing material substantially rectangular in shape and having a granular surfacing on one side, said strip being provided with spaced rectangular notches extending inwardly from the lower edge and integrally connected overlying portions folded upon and attached to the surface of the strip, said integrally connected portions comprising the material severed between individual sets of notches, a portion of the outer end of each overlying portion forming a shoulder with which the edge of an overlying strip is adapted to align and abut.
3. A new article of manufacture comprising a strip of flexible roofing material substantially rectangular in shape and having a granular surfacing on one side, said strip being provided with spaced rectangular notches extending inwardly from the lower edge and integrally connected overlying portions folded upon and attached to the sur-

face of the strip, said integrally connected portions comprising the material severed between individual sets of notches, the exposed surface of the overlying folded portions presenting fields of different colors than the body of the strip, a portion of the outer end of each overlying portion forming a shoulder with which the edge of an overlying strip is adapted to align and abut.

4. A new article of manufacture comprising a strip of flexible roofing material substantially rectangular in shape and having a granular surfacing on one side, said strip being provided with spaced rectangular notches extending inwardly from the lower edge and integrally connected overlying portions folded upon and attached to the surface of the strip, said integrally connected portions comprising the material severed between individual sets of notches, the upper edges of the overlying folded portions forming shoulders against which the lower edges of overlying strips are adapted to abut and with which they automatically align.

HARRY A. CUMFER.
